SPACE HEATER CABINET

John B. Mathis, Chicago, Ill., assignor to Florence Stove Company, Gardner, Mass., a corporation of Massachusetts

Application January 4, 1957, Serial No. 44,408

Term of patent 3½ years

(Cl. D81—10)

Figure 1 is a perspective view of a space heater cabinet equipped with a front construction embodying my new design.

Fig. 2 is a view, partially in cross section, taken along the line 2—2 of Fig. 1.

The characteristic features of my design reside in the portion shown in full lines in the drawing.

I claim:

The ornamental design for a space heater cabinet, as shown and described.
